CLAIM

The ornamental design for a rolled and decorated cupcake, as shown and described.

DESCRIPTION

FIG. 1 is a front, right perspective view of a rolled and decorated cupcake illustrating the first embodiment of my invention;

FIG. 2 is a top plan view of FIG. 1;

FIG. 3 is a bottom plan view of FIG. 1;

FIG. 4 is a rear elevation view of FIG. 1;

FIG. 5 is a front elevation view of FIG. 1;

FIG. 6 is a right side elevation view of FIG. 1;

FIG. 7 is a left side elevation view of FIG. 1;

FIG. 8 is a front right perspective view of a second embodiment of my invention;

FIG. 9 is a top plan view of FIG. 8;

FIG. 10 is a bottom plan view of FIG. 8;

FIG. 11 is a rear elevation view of FIG. 8;

FIG. 12 is a front elevation view of FIG. 8;

FIG. 13 is a right side elevation view of FIG. 8; and,

FIG. 14 is a left side elevation view of FIG. 8.

The broken lines in the drawings illustrate portions of the rolled and decorated cupcake that form no part of the claimed design.
